UNITED STATES PATENT OFFICE.

EDWIN O. KLEMM, OF DAYTON, OHIO, ASSIGNOR TO KLEMM MANUFACTURING COMPANY, OF SAGINAW, MICHIGAN.

STOP MECHANISM FOR GRAPHOPHONES.

1,385,690.

Specification of Letters Patent. Patented July 26, 1921.

Application filed July 15, 1919. Serial No. 310,910.

To all whom it may concern:

Be it known that I, EDWIN O. KLEMM, a citizen of the United States, residing at Dayton, in the county of Montgomery and 5 State of Ohio, have invented certain new and useful Improvements in Stop Mechanism for Graphophones, of which the following is a specification.

This invention appertains to the art of 10 graphophones and involves particularly a certain novel controlling and stopping mechanism for such machines.

An important feature of the invention resides in the provision of stop mechanism 15 susceptible of manual or automatic action at the will of the operator of the sound producing machine.

A second important feature of improvement devised by me resides in certain trip 20 and detent devices employed in my mechanism whereby the time of operation of the machine may be varied to accommodate for the production of records of different sizes.

Another highly essential object of my invention has been to devise provisions such 25 that the controlling of the starting and stopping of the graphophone is made a part of the exclusive function of the tone or reproducer arm. In other words I have so de- 30 signed the stopping device, and parts intermediate the said device and the reproducer arm, that by proper manipulation of the latter the motor by which the record carrier or table is actuated may be caused to start the 35 operation of the said carrier; other manipu- 40 lation of said arm may be caused to pre- determine the point on the record, whether at the end or any other part of the record, where the stopping of reproduction will 45 take place; and the customary movement on manipulation of the tone arm may be em- 50 ployed to carry it to the proper point for deposit on the record to start the reproduction. Obviously the embodiment in the tone 55 arm itself of the starting and stopping control functions, respecting reproduction of records of different sizes by the graphophone, is a very practical desideratum in the art because under such conditions the necessity of a separate manual or other device to control the starting, at least, is avoided. I, therefore, deem this part of my invention broadly new and my claims there- 60 fore, are to be read not as covering the spe- 65 cific instrumentalities by which I accom-

plish this new object but as permitting wide variation in regard to the means employed for the purposes in view.

Finally an especial object had in view in developing the improvements hereof has 60 been to simplify to the greatest possible degree, the construction of the several controlling parts which will be hereinafter seen to be few in number, easily made, readily assembled, and absolutely positive as regards 65 adjustments and operation.

A complete understanding of the invention including the advantages for its use in practice, will be had on study of the following description in conjunction with the an- 70 nected drawings, in which:—

Figure 1 is a view in elevation, with the reproducer arm and trip shown partially in section, illustrating certain conventional graphophone devices with the improvements 75 hereof applied thereto.

Fig. 2 is a fragmentary top plan view bringing out more clearly the arrangement of the shaft, brake and other controlling parts. 80

Fig. 3 is a detached perspective view showing particularly the trip, detent, and brake elements forming the essential parts of my invention, the brake arm and detent parts being shown in dotted lines as when the ma- 85 chine is in operation, in full lines as positioned during the preliminary adjustment of the trip.

Fig. 4 is a fragmentary sectional view 90 on the line 4—4 of Fig. 1.

Fig. 5 is a corresponding sectional view taken about on the line 5—5 of Fig. 1 showing only the brake arm and governor parts with which the brake means coacts. 95

Fig. 6 is a fragmentary sectional view about on the line 6—6 of Fig. 1, illustrating the detent arm in full lines as when ar- 100 ranged for preliminary adjustment of the trip, and in dotted lines as when the trip is traveling over said detent arm, and as when the detent arm has been moved to a position for the starting of the graphophone.

Fig. 7 is a perspective view of a modified adaptation of the invention.

Fig. 8 is a sectional view, partly in eleva- 105 tion, of said modification.

Fig. 9 is a sort of diagrammatic view to show the peculiar movement of the repro- 110 ducer arm in controlling stopping and start- ing of the motor.

In the drawings and the description forming the specification hereof, similar reference characters refer to similar parts throughout.

- 5 Taking up the general construction of the machine to which my invention is applied, it may be noted that said machine comprises a suitable base A which may be a portion of a cabinet of one of many different types. To the under side of said base A is attached the customary motor frame, the motor of which is adapted to drive the spindle C which supports and turns the record table or platform D. The reproducer 10 arm E with its reproducer F are largely of the common type in use, the arm being slightly modified as hereinafter set forth to provide a special mounting for the trip means of my invention.
- 15 20 The starting and stopping of the motor, not shown, is controlled in what is largely the known manner, by brake means arranged to coact with the disk 1 of the governor 2.

The foregoing sets forth those parts which 25 are largely conventional, and the parts which comprise my invention will now be described.

Attached to the motor frame B is a supporting plate 3 seen best in Fig. 1, the ends 30 of said plate being out turned and having openings forming bearings for the shaft 4. The shaft 4 has one end extended upwardly to provide a controlling lever. The opposite end of the shaft 4 is extended upwardly 35 but terminates short of the base A to form the detent arm 6. The arm 6 is of rather peculiar form being projected laterally as shown at 6^a and downwardly as shown in 6^b, for a purpose to be shortly disclosed. On 40 the shaft 4 is secured, preferably detachably, the brake arm 7 having the shoe 8 at its free end beneath and adapted to engage the disk 1 of the governor 2.

One of the extensions at the end of the 45 plate 3 has a lateral projection 9 with which is connected the coiled spring 10. The spring 10 is likewise connected with the upper portion of the arm 6 as shown at 10', and the normal action of the spring 10 is 50 to rock the shaft 4 so as to cause engagement of the shoe 8 with the governor disk 1.

I utilize two means for maintaining the 55 brake device inactive in relation to the governor 2, one means forming a part of the automatic controlling devices for the stop or brake mechanism, and the other means adapted to render the means just above referred to inoperative to perform its function, and to hold the brake device inactive 60 until restored to activity by manipulation of certain parts by the operator.

Taking up the automatic means first it is notable that the reproducer arm E is threaded near its point of support as shown 65 at 11 and the socket member 12 of a trip

13 is likewise threaded to screw upon said threaded portion 11 of the reproducer arm. The trip 13 thus has a friction connection with the arm E and the trip 13 is bent downwardly and laterally to form the arm 70 14 arranged to coact with the detent arm 6.

The mode of operation of the parts just set forth is as follows:

It should be borne in mind that the lever or arm 5 of the shaft 4 extends upwardly 75 through a slot 15 in the base A and said lever 5 is movable by the hand and adapted to occupy 3 positions shown in full and dotted lines in Fig. 4. Assuming that a record has been placed upon the table D, 80 to adjust the mechanism for the playing of said record and the stopping of the machine at the end of the record, the operator grasps the reproducer arm E and shifts the same with a motion of the reproducer from the 85 center of the table D outward. The reproducing needle or stylus is then deposited on the last sound groove of the record. The motor being maintained out of action by the engagement of shoe 8 with governor disk 90 1, the parts are now in substantially the positions shown in Figs. 1 and 3. That is to say, the described movement of the reproducer arm has brought the trip arm 14 against the portion 6^b of the detent arm 6, 95 and said arm 14 by slight turning on the reproducer arm E is therefore located in the position it will occupy when the reproducer reaches the end of the record. To start the machine, the operator pulls the 100 lever 5 from the stopping position occupied by it, as shown in Fig. 3, and designated α in Fig. 4, to its starting position designated α' in Fig. 4. The movement of the lever 5 in this manner disengages the brake means 105 from the governor disk 1, as shown by dotted lines in Fig. 3, and lowers the portions 6^b and 6^a of the detent arm 6, also as shown in Fig. 3. The operator holds the lever 5 in the starting position α' aforesaid, momentarily, and then shifts the reproducer arm 110 E to carry the reproducing needle to the first or outer groove and deposits the needle there. The lever 5, may now be released and the spring 10 will act to lift the horizontal portion 6^a of the arm 6 up against the under side of the trip arm 14. In this way the detent arm 6 is prevented from tilting to its normal stopping position, the brake shoe 8 being thus detained or prevented from engagement with the disk 1, so long as the arm 115 14 engages the portion 6^a of the arm 6. Obviously, however, after the reproducer has traversed the record, on coming to the end of the record, the trip 14 which moves with the 120 reproducer, on account of its frictional connection, passes off of the portion 6^a, so that the spring 10 acts on the arm 6 to rock said arm to the shaft 4, to raise the shoe 8 into 125 stopping engagement, with the governor 130

disk 1. The machine is thus automatically stopped at the predetermined time necessary for a complete operation of the record. This predetermined time is, of course, variable according to the length of the record by reason of the peculiar coaction of the parts 14, 6^b, and 6^a.

During the time when the sound record is being played, the lever 5 occupies the position shown at y in dotted lines, in Fig. 4, the shaft 4 being partially tilted back from its stopping position.

In Fig. 6, the full and dotted line positions of the arm 6 and its portion 6^a and 6^b, correspond with the positions of the lever, as shown in Fig. 5, and the several positions of the arm 6 are, therefore, designated x', y' and z'.

Should it be desired to maintain the automatic stopping devices out of action, I resort to the simple expedient of moving the lever 5 to the position x, of Fig. 5 and temporarily locking said lever in such position by a hook 16.

If the operator should desire to employ the stop mechanism after the manner of the usual hand controlled stop mechanisms of graphophones, the hook 16 is used to maintain the lever 5 at its starting position, or with the brake released until stopping of the record is necessary, whereupon the lever 5 is unhooked. If on unhooking the lever 5 the reproducer F has traveled sufficiently far to carry the arm 14 off of the portion 6^a of the detent arm 6, obviously the spring 10 will cause the application of the brake 8 and stopping of the motor. It may be, however, that when the operator wants to stop the machine, and release the lever 5, the trip arm 14 may still engage the portion 6^a of the arm 6. Under these conditions, the operator simply carries the reproducer arm E to about the center of the record to make sure that the trip 13 does not coact with the part 6^a to prevent the application of the brake.

The advantages of my mechanism will be apparent when it is recognized that I utilize about six parts only in the construction of my devices and all these parts are simply formed, adapted to be cheaply made, and may be very easily put together and applied to popular types of machines. Instead of the screw thread connection of the trip collar 12 with the reproducer arm E any suitable frictional connection may be employed.

Figs. 7 to 9 inclusive show the modified adaptation of the invention wherein I utilize the tone arm E in peculiar coöperation with the detent arm 6 for causing the starting of the movement of the carrier on table D. It will be remembered that according to the construction before described herein, the starting of the motor is accomplished through the manipulation of the lever 5. By my modified construction I am enabled to

dispense with the lever 5 entirely. In fact, as shown in Fig. 7, it will be observed that the shaft 4' terminates just beyond where the brake arm 7 is attached thereto. The parts in Figs. 7 to 9 which are substantially the same or equivalent to those described in the first form of my invention set forth herein, have like reference characters. I might note, however, that the reproducer arm E according to my modified construction should preferably be one of the type having the usual universal joint connection E' with the base A, shown in Fig. 8. I have illustrated the trip 13' with its lateral portion 14 in a form which frictionally engages the tone arm near the universal joint E'. This trip forms an invention separate entirely from this application. The trip 13' works practically the same as the trip 13 previously described.

Understanding the construction of the parts in a modified form as per the slight differences just set forth, it is notable that the following peculiar operation of the parts for controlling the stopping point and starting of the carrier D and the record thereon may be obtained. Assuming that the reproducer needle occupies a position at rest about at the center of the record, and referring to Fig. 9, to adjust the reproducer for stopping of the record at the end of the record brake, the operator will grasp the reproducer arm E, elevate the same slightly and shift the arm outwardly, say from A' to B' according to the diagrammatic illustration of Fig. 9. In this way the member 14 of the trip 13 is caused to engage the part 6^b of the detent arm 6 effecting a proper adjustment of the trip 13 for a predetermined stopping point, in this instance, at the inner end of the record track. Thereafter the arm E is raised and caused to traverse a path something like that shown from B' to C' in Fig. 9, the member 14 in this way being caused to depress the portion 6^a of the arm 6, in such a manner as to disengage the brake shoe 8 from the governor disk 1. The operation of the carrier D is thus started by the motor when released in this manner. Thereafter the operator merely shifts the reproducer say from the point C' to the point D' as designated in Fig. 9, assuming the point D' to be the position at which the arm E should be deposited for commencement of reproduction of the record.

I contemplate that there may be two variations of the mode of operation just described. In the first place the adjustment of the reproducer arm E preliminarily to control the stopping point may be at any point to bring the needle to any point in the length of the record during the preliminary outward adjustment and before the raising movement characterized as B' to C' in Fig. 9 commences. Again, the op-

erator may of course, deposit the needle at any point in the length of the record for starting; he does not have to deposit it at the outer end of the track of the record.

- 5 Obviously where the tone arm E has a universal joint connection with the base A, the mode of operation just set forth may be used with the construction of detent arm 6, brake parts, and lever 5, shown clearly in
 10 Fig. 3 under which conditions moreover the arm E or the member 5 may be employed to control starting, at the option of the user of the machine. However, the evident simplicity of control obtained by me according to my construction in Figs. 7 to 9, is a great advantage from practical and commercial view points owing to both simplicity of structure and operation.

Having thus described my invention what
 20 I claim as new is:—

1. Graphophone mechanism comprising in combination, a record carrier and a reproducer to traverse a record on said carrier, driving mechanism for the carrier, stop means for the driving mechanism, including a brake member and a spring to render said member effective, a member to manually operate the brake, and means to lock said member in a predetermined position.
 25 2. Graphophone mechanism comprising in combination, a record carrier and a reproducer to traverse a record on said carrier, driving mechanism for the carrier, stop means for the driving mechanism, including a brake member and a spring to render said member effective, a lever to manually operate the brake, and means to lock the lever in a position holding the brake member inactive.
 30 3. Graphophone mechanism comprising in combination, a record carrier and a reproducer to traverse a record on said carrier, driving mechanism for the carrier, stop means for the driving mechanism, including a brake member, an arm carrying the reproducer, a trip on the reproducer arm movable with and independently thereof, and a detent connected with the brake member to control the operativeness thereof, said 35 detent embodying an arm having a portion to engage and cause movement of the trip relatively to the arm, and a second portion to engage the trip and to be restrained from movement by the trip, and spring means to move the detent arm when the restraining influence of the trip is removed therefrom.

4. Graphophone mechanism comprising in combination, a record carrier and a reproducer to traverse a record on said carrier, driving mechanism for the carrier, stop means for the driving mechanism, comprising a rock shaft, a lever arm on said shaft to manipulate it, a brake member carried by the shaft, a detent arm on said shaft to

control the action of the brake member, and a trip operable by the reproducer and adapted to coact with the detent arm.

5. Graphophone mechanism comprising in combination, a record carrier and a reproducer to traverse a record on said carrier, driving mechanism for the carrier, stop means for the driving mechanism, comprising a rock shaft, a lever arm on said shaft to manipulate it, a brake member carried by the shaft, a detent arm on said shaft to control the action of the brake member, a trip movable by the reproducer, and adapted to engage the detent arm, and spring means to maintain coaction of the trip and detent arm. 70
 75

6. Graphophone mechanism comprising in combination, a record carrier and a reproducer to traverse a record on said carrier, driving mechanism for the carrier, stop means for the driving mechanism, comprising a rock shaft, a lever arm on said shaft to manipulate it, a brake member carried by the shaft, a detent arm on said shaft to control the action of the brake member, a trip movable by the reproducer, and adapted to engage the detent arm, and spring means to maintain coaction of the trip and detent arm. 80
 85

7. Graphophone mechanism comprising in combination, a record carrier and a reproducer to traverse a record on said carrier, driving mechanism for the carrier, stop means for the driving mechanism, comprising a rock shaft, a lever arm on said shaft to manipulate it, a brake member carried by the shaft, a detent arm on said shaft to control the action of the brake member, a trip operable by the reproducer and adapted to coact with the detent arm, and a lock for holding the shaft in a position preventing coöperation of the detent arm and trip. 90
 95

8. Graphophone mechanism comprising in combination, a record carrier and a reproducer to traverse a record on said carrier, driving mechanism for the carrier, stop means for the driving mechanism, comprising a rock shaft, a lever arm on said shaft to manipulate it, a brake member carried by the shaft, a detent arm on said shaft to control the action of the brake member, a trip operable by the reproducer and adapted to coact with the detent arm, and a lock to hold the lever arm in a position preventing coöperation of the trip and detent arm. 100
 105

9. Graphophone mechanism comprising in combination, a record carrier and a reproducer to traverse a record on said carrier, driving mechanism for the carrier, stop means for the driving mechanism, comprising a rock shaft, a brake member on said shaft, a detent arm on said shaft, a reproducer arm, a trip movable with and independently 110
 115
 120
 125
 130

of the reproducer arm, and manual means to hold said shaft in a position maintaining the brake member ineffective.

10. Graphophone mechanism comprising
5 in combination, a record carrier and a reproducer to traverse a record on said carrier, driving mechanism for the carrier, stop means for the driving mechanism, comprising a rock shaft, a brake member on said
10 shaft, a detent arm on said shaft, a reproducer arm, a trip movable with and independently of the reproducer arm, manual means to hold said shaft in a position maintaining the brake member ineffective and a
15 locking device to hold the shaft in said position maintaining the brake means ineffective.

11. Graphophone mechanism comprising
in combination, a record carrier and a reproducer to traverse a record on said carrier, driving mechanism for the carrier, stop means for the driving mechanism, comprising a rock shaft, a brake member on said
20 shaft, a detent arm on said shaft, a reproducer arm, a trip movable with and independently of the reproducer arm, manual means to hold said shaft in a position maintaining the brake member ineffective and a
25 locking device to engage said manual means
30 to hold the same in a predetermined position.

12. Graphophone mechanism comprising

in combination, a record carrier and a reproducer to traverse a record on said carrier, driving mechanism for the carrier, stop
35 means for the driving mechanism, comprising a rock shaft, a lever arm on said shaft to manipulate it, a brake member carried by the shaft, a detent arm on said shaft to control the action of the brake member, a trip
40 operable by the reproducer and adapted to coact with the detent arm, a spring for controlling coöperation of the detent arm and trip, and manual means to interfere with the action of the spring.

13. Graphophone mechanism comprising
in combination, a record carrier and a reproducer to traverse a record on said carrier, driving mechanism for the carrier, stop
45 means for the driving mechanism, comprising a rock shaft, a lever arm on said shaft to manipulate it, a brake member carried by the shaft, a detent arm on said shaft to control the action of the brake member, a trip
50 operable by the reproducer and adapted to coact with the detent arm, said detent arm having a bent end portion to abut and move the trip relatively to the reproducer, and having another bent portion to hold the
55 shaft in a certain position during movement
60 of the reproducer while traversing the record.

In testimony whereof I affix my signature.
EDWIN O. KLEMM.
